11 Claims. (Cl. 60—39.28)

1

This invention relates to the control of internal combustion engines such as that of a turbo jet engine used in aircraft. More particularly, this invention relates to novel fluid actuated means for controlling fuel supply and other conditions of the engine.

It is an object of this invention to provide means to remotely control a throttle in the engine fuel supply which operates in conjunction with a valve system that maintains a constant pressure drop across the throttle thereby permitting uniformity of action of the remote control means independent of resistance of fuel flow into the engine.

Another object resides in preventing the remotely controlled throttle from moving to cut off the fuel supply entirely and in the provision of manually controlled means which operate to cut off the fuel supply if the operator so desires.

Another object is the provision of means to permit manual selection of engine speed and means to automatically maintain engine speed at the selected value.

A further object of one embodiment of our invention is to make a remote control of the throttle sensitive to small persisting speed variations, the control being relatively insensitive to very small oscillatory speed variations.

A further object of one embodiment of our invention lies in the protection of the engine from too rapid acceleration and excessive combustion chamber temperatures. We accomplish this object by providing means in the control system which slow down the acceleration of the engine relative to the deceleration.

A further object of another embodiment of our invention lies in the provision of a pressure controlled governing switch and remote control means to position said switch in order to energize an electric circuit that may control propeller pitch governing motor or any other controlling device.

These and other objects will be apparent as the following detailed description of our invention proceeds.

In the drawings:

Fig. 1 is a schematic view of one embodiment showing the fluid and hydraulic circuits; and

Fig. 2 is a schematic drawing of a second modification of our invention.

In the modification shown in Fig. 1, there is a hydraulic circuit which controls the throttle in such a manner as to maintain the speed of the turbine constant representing a given setting of the manually controlled condition lever. The

speed itself is selected by the condition lever in accordance with the work to be done and the actual speed attained by the engine is sensed by a variable pressure pump driven by the engine, which pump is part of a hydraulic control mechanism that automatically adjusts fuel flow until the selected speed is attained.

The constant speed hydraulic circuit which controls the fuel flow operates in conjunction with an electric circuit which controls the load in a novel manner so that the temperature in the combustion chamber of the engine is maintained at a preselected value. The details of the electric circuits which may be employed to accomplish this are fully described in the co-pending application of A. Rood, Ser. No. 711,961, filed Nov. 23, 1946. Basically, this is accomplished by measuring the temperature in the combustion chamber, correcting it for heat transfer lag, comparing the corrected temperature with the selected temperature, causing any difference therein to increase or decrease pitch of the propeller thereby increasing or decreasing the load proportionately. For example, if the actual temperature is higher than the selected temperature the novel arrangement described in the aforesaid co-pending application will automatically decrease the pitch of the propeller thereby decreasing the load on the turbine and cause the temperature in the combustion chamber to drop. This arrangement is particularly effective because it is in combination with the constant speed fuel supply circuit. This combination makes it possible to automatically compensate for differences in engine operating conditions due to variations in altitude and also variations of fuel requirements due to changes in engine efficiency at various speeds.

The circuits which control the fuel can be divided into three major divisions; first, the fuel circuit itself; second, the hydraulic control or servo circuit; and third, the sealed throttle actuating circuit. Although we have illustrated diagrammatically one type of engine which may be employed, it will be understood that we have merely done this to illustrate an application of our invention, and although the jet or turbine engine presents certain special problems which are solved by our apparatus, we do not limit ourselves to utilization of our novel control means with any one engine design unless said design is claimed. The engine may have a gas turbine which is driven by burning of fuel mixed with air in the combustion chamber. One or more air compressor stages 2 may be driven by the turbine

shaft 3 to supply the necessary air. The turbine shaft usually drives a gear reduction unit 4 which turns the propeller 5. We contemplate the use of a variable pitch propeller, one form of which may have an electric motor to change propeller pitch indicated generally at 6.

The main fuel supply line 10 connects to the fuel pump which may be a positive displacement pump and which supplies fuel under pressure to line 11. The throttle is automatically positioned as will be described presently and acts to determine the amount of fuel which flows into line 12 and hence into the combustion chamber at 13. A cut-off valve, spring urged to a closed position, is normally held open by the fuel pressure but if that pressure drops below a predetermined value, the cut-off valve will close and prevent fuel from entering the combustion chamber at low pressures. In order to make the amount of fuel which flows into the combustion chamber a direct function of throttle position independent of fuel pump pressure and of the orifice resistance in the chamber, it is desirable to have a constant pressure drop occur across the throttle. In order to accomplish this a constant pressure difference by-pass valve and a pressure difference control pilot are provided. The pressure difference valve fits in a cylinder one end of which connects by line 11a to the throttle inlet line 11. The valve close off passageway 18 so that passageway chamber 16 behind the valve to gradually build up and almost equal that in line 11a. Spring 17 urges the constant pressure difference valve to the right to close a by-pass line 10a by-passing fluid from line 11 to supply line 10, so that the higher the pump pressure the greater the by-pass. A line 12a leads from the throttle outlet 12 and fuel in this line is at the pressure necessary to force fuel through the nozzle in the engine. Pressure in line 12a urges the pressure difference control pilot to the right in the drawing so that it tends to close off the passageway 18 and hence tends to seal off the left end of the constant pressure difference by-pass valve, urging the by-pass valve to the left.

Assume that for some reason or other pressure of the fuel entering the combustion chamber through passageway 12 does not change but that fuel pressure in passageway 11 from the pump increases. The increase in pressure in line 11 will cause the constant pressure difference valve to move to the left which will tend to by-pass high-pressure fuel by means of line 11a into the low pressure line 10a, thus reducing pressure in line 11. The valves are designed so that this action continues until the pressure difference across the throttle, that is between lines 11 and 12, is at the predetermined value. Assume now that the pressure in line 11 from the fuel pump remains constant but that pressure in line 12 leading from the throttle to the combustion chamber increases, due to a restriction in the nozzle, for example. It will be noted that a certain amount of fluid from line 11a always tends to pass through orifice 15 in the pressure difference valve and pressure within the chamber 16 and behind the valve tends to equal the pressure in the high-pressure fuel line 11. Under normal operating conditions the pressure difference pilot does not completely close off passageway 18 so that passageway 18 can communicate with a line 10b connected to the low-pressure side of the fuel pump. However, due to the throttling action at the pressure difference pilot there will be a pressure built up behind the pressure difference valve which pres-

sure will augment the force of spring 17 tending to move that valve to the right and tending to shut off the by-pass between chamber 11a and low-pressure line 10a. Now, if the pressure increases in line 12 it is necessary to increase the pressure in line 11 an equal amount to maintain a constant pressure drop across the throttle. This is accomplished as the pressure difference pilot moves to the right under the increased pressure in line 12a, tending to restrict the exhaust from chamber 18 into the low pressure line 10b and causing more pressure to build up behind the constant pressure difference valve. That valve now moves to the right and decreases the by-pass from line 11a into the low pressure line 10a. The valves are arranged so that this action continues until pressure from the fuel pump in line 11 increases by the same amount that the pressure in the nozzle line 12 was increased. Thus, it can be seen that the constant pressure difference valve will maintain a constant pressure drop across the throttle regardless of whether there is a pressure change in the fuel pump line 11 or in the delivery line 12 to the engine, or in both lines.

Having completed the description of the fuel feed circuit, the hydraulic control pressure circuit and its actuation of the sealed throttle actuating circuit will be described. In the modification shown in Fig. 1, a sump tank which attains a supply of oil or other fluid for actuating the control circuit is illustrated schematically in the drawing. A pair of pumps which may be driven by the engine, one being arranged to deliver constant pressure and the other being arranged to develop a pressure which is proportional to engine speed are provided. The constant pressure pump discharges into the line 20 and forces fluid through the orifice 15, pressure regulation being afforded by the regulating relief valve R which bypasses line 21 to exhaust line 22. The constant pressure fluid is conducted by means of line 23 to one side of a governor circuit selector shuttle valve. The variable pressure pump discharges in the line 24 at a pressure which is proportional to engine speed squared. A variable circuit relief valve V may be provided to limit the pressure in line 24. The flow of fluid in the variable pressure lines 24 and 24a is by-passed partially by a profiled portion 25 of a selector valve into an exhaust line 22a. The selector valve may be manually positioned in any convenient means to regulate the pressure of by-pass and, as will be explained presently, position of the selector valve eventually determines the speed of the turbine. The selector valve may be positioned by a condition lever, the position of which may be calibrated in terms of the condition under which the pilot wishes the plane to operate as indicated on the drawings.

One side of the governor selector shuttle valve is acted upon by constant pressure in line 23 and the variable pressure in line 24a acts on the other side. Under equilibrium conditions engine speed seeks a value such that pressure in the variable line 24a equals that in constant pressure line 23 for all selector valve positions. The constant pressure fluid enters passageway 26 and may be bled into either of lines 30 or 31 which form control lines for the sealed throttle actuating circuit. The sliding sealing piston 33 transmits changes in pressure in line 30 into a sealed chamber 35 which, in turn, transmits the change in pressure to chamber 36 on one side of a piston 37 which forms an acceleration-deceleration control unit.

Sealing piston 33 insures that no dirt will find its way to metering groove in piston 37. Piston 37 is slideable to a limited extent and is urged to the left by fluid pressure in chamber 36 and to the right by fluid pressure in chamber 38 and also by spring pressure of spring 39. This piston is provided with a fine spiral groove which permits a metered amount of oil flow through the piston. For example, if line 30 is opened to a source of fluid under pressure, sealing piston 33 moves left, a metered quantity of oil flows into chamber 40 and exerts a force against the sealed end 41 of the profiled throttle. Conversely, if line 31 is opened to a source of fluid under pressure the other end 42 of the throttle is acted upon by pressure in chamber 32. The position of the throttle is determined by the flow of fluid in lines 30 and 31 which, in turn, depends on the position of the governor selector shuttle.

The acceleration and deceleration piston 37 modifies the effect somewhat in the following manner. Assume that equilibrium exists in that engine speed equals selected speed, whereupon the manual condition lever is set for less speed. The by-pass effect of profile 25 of the selector valve is then reduced so that pressure in line 24a increases and initially exceeds that in the normally constant pressure line 23. With this increase of pressure in line 24a, the shuttle valve is moved up and bore 26 in the shuttle valve connects constant pressure line 23 to line 30, and line 31 is connected to exhaust by line 22b. Fluid tends to flow into line 30 and pressure builds up to the right of the sealing piston 33. This increases the pressure in chamber 35 and hence in chamber 36 and tends to force fluid through the spiral groove in the piston 37. Furthermore, pressure against the end of piston 37 in chamber 36 moves the piston to the left. Motion of the piston to the left decreases the length of the restriction caused by the spiral groove, the purpose of this action being to make deceleration somewhat more rapid than acceleration, in order to prevent excessive build up of heat in the combustion chamber. The fluid that flows through the spiral groove added to the fluid flow caused by motion of the piston 37 to the left creates additional pressure in chamber 40 which acts against the face 41 of the throttle causing it to move to the right. When this occurs the profiled portion 43 of the throttle restricts the flow of fluid into the line 12 and hence into the combustion chamber at 13. Simultaneously, fluid is displaced from chamber 32 into the exhaust so there is no hydraulic block on the throttle. As soon as engine speed drops to the selected speed, pressure in line 24a drops to equal that in line 23. The shuttle valve may still be displaced from neutral but this merely means that the throttle overshoots to return the shuttle valve. Thus the throttle hunts somewhat until the selector valve centers whereupon there is no further motion of the throttle.

Once the selector valve is positioned to select a certain speed the action of the variable pressure pump against the governor selector shuttle will continuously adjust the throttle to maintain the speed at the selected value.

The governor selector shuttle arrangement herein described makes available the full pressure in the constant pressure system for actuation of the throttle which provides a very sensitive control. No matter how small the variation in actual engine speed from selected speed may be, if that variation exists over any appreciable

period of time the selector shuttle will move to connect one of the throttle control lines to full constant line pressure. This gives a positive and certain correction of very small speed variations, even though there might be some tendency for the valves to stick or even though the system might tend to be somewhat sluggish in operation. The advantages of this arrangement can be readily understood if it is compared with one wherein the pressure variations in the variable pressure line due to speed changes operate the throttle directly. If this were the case a slight variation in speed and its attendant slight variation in pressure in the variable pressure line might not be enough to break loose the throttle and move it. In our system we need only move a pilot valve which may be relatively light and free of movement, to apply full constant line pressure to actuate the throttle. Also, we can make the lands on our pilot valve or selector shuttle valve slightly wider than the ports which they close so that slight oscillatory variations in speed will not be transmitted to the throttle and cause undue hunting. However, if the slight variation in speed persists for any appreciable period of time, the shuttle valve will drift over in the proper direction to correct that variation.

If a speed increase is desired the selector valve is positioned to by-pass more fluid and decrease the pressure in line 24a so that the shuttle valve is moved down. In this case fluid flows into line 31 and chamber 32 whereupon it acts upon the face 42 of the throttle to move the throttle to the left. This gives an increased fuel flow through line 12 and more fuel reaches the combustion chamber. It will also be noted that acceleration cannot be effected as quickly as deceleration because when the throttle is moved to the left it forces fluid from chamber 40 against the left end of the piston 37. This causes the piston to move to the right and imposes the full length of the spiral groove in the path of fluid transfer in chamber 39 to chamber 36. The result is that an overly rapid increase of fuel flow to the combustion chamber is prevented. The deceleration adjustment shown limits the motion of the piston 37 to the left and thereby controls the amount by which the restricted orifice is opened up which, in turn, controls the relative rapidity of deceleration and acceleration. Likewise, the acceleration control screw can be adjusted so that piston 37 will not move so as to prevent the complete spiral groove if it is desired to have more rapid acceleration.

A viscosity control heater coil is shown surrounding the piston 37 which coil is connected to the main power supply and may be controlled by a thermostat located in the oil adjacent the piston 37. With this arrangement, oil viscosity at the piston 37 and the calibration of the adjustment is maintained constant regardless of external temperatures.

A burner blowout adjustment screw 45 may be provided to limit closing of the throttle below that point where the burner will blow out. In most jet or turbine engines it is desirable to have the fuel supply cut off completely when the manual control is set to its off position and yet it is not desirable that the throttle itself be permitted to move to a position where the burner will blow out unless such a position is manually selected. This creates a problem where the throttle is controlled by a remote control or servo system, so the burner blowout screw is adjusted to prevent unselected burner blowout.

We also provide an automatic cut-off valve between the line 12 and combustion chamber at 13 which is spring-urged to a closed position by a light spring so that when the pressure in line 12 drops below a certain predetermined value, even though that pressure may not be zero, no fuel can flow into the combustion chamber. Likewise, if the condition lever is set to the off position, we provide means to completely cut off the fuel supply by connecting a cut-off pilot so that it is moved with the selector valve. In the off position of the selector valve, the cut-off pilot valve opens a line 52 to low pressure line 10c, branching from the main fuel supply line 10. When this occurs pressure behind the constant pressure difference valve drops rapidly and that valve is moved to the left by fuel pump pressure in line 11a. This by-passes fuel pump pressure from line 11 into line 10a and back to the supply line 10. Simultaneously pressure in the throttle outlet line 12 drops to the value at which the cut-off valve can close, so that fuel is completely cut off from the combustion chamber even though the throttle itself can never be completely closed by the servo control system.

In the modification shown in Fig. 2, results similar to those just described in the first embodiment are attained except the hydraulic and electric circuits are interchanged in such a manner that the hydraulic system regulates the load to hold a selected turbine speed, whereas the temperature measuring and lag correction system regulates the fuel supply to maintain a selected absolute temperature in the combustion chamber. The constant and variable pressure pumps and associated regulators, and the action of the selector valve is like that in the previously described form. However, instead of connecting the constant and variable pressure lines to a selector shuttle valve, they connect to opposite ends of an electro-hydraulic piston assembly which we refer to as the propeller governing switch. The constant pressure line 23 communicates with a chamber 50 on one side of the propeller governor switch and the variable pressure line 24a connects to chamber 50a on the other side thereof. It will be remembered that under equilibrium conditions the speed of the engine automatically attains such a value that the pressure in line 24a equals that in line 23, and the turbine speed necessary to cause such equalization of pressures is determined by the position of the speed selector valve. Normally, the propeller governor switch is centered in its cylinder in the off position, and a pair of opposed springs tend to keep the switch in its neutral position. Each end of the switch has an arm or other support means 52 and 52a respectively which carry the movable arm of variable resistance shown schematically in the drawing. Each resistance 52 and 52a is connected to one input of the propeller pitch changing motor. In order that direction of flow to the motor will be such as to effect the necessary increase or decrease in load and in order that the amount of current flow to the propeller motor will depend upon the amount of variation between the actual speed and the selected speed, a pair of resistances are provided in the governing switch as illustrated schematically in the drawings. The pair of resistances 54 and 54a are connected together to one side of the power supply and each of the resistances may be engaged by its associated resistance arm 52 and 52a respectively, depending upon which way the piston is moved from neutral. A pair of stationary contact members 53 and 53a

are also in position so that one of these members is engaged by the arm 52 or 52a depending upon which way the switch is off neutral, in order to complete the circuit. These fixed contact members are connected together and to the other side of the power supply. There is a small dead space at neutral to keep very small speed changes from energizing the propeller pitch motor.

The governor switch acts as follows: Assume that a speed has been selected and that turbine speed becomes greater than the selected speed. In this case pressure in line 24a will exceed that in the constant pressure line 23 and the switch will move to the right. This will cause arm 52a to connect to engage the fixed contact 53a so that line 53 leading to the propeller motor will be connected to the power supply. The other arm 52 will engage the resistance 54 thereby connecting line 59 from the motor to the other power supply line but through the resistance 54. The greater the displacement of the switch piston the less resistance there will be in the circuit and the more the motor will be energized. When this occurs in the assumption made, the propeller pitch will be increased, increasing the load and causing the turbine to slow down until actual and selected speeds are equal. As this occurs pressure in line 24a gradually drops until it again equals pressure in the constant pressure line 23, whereupon the governor switch piston overshoots and is rapidly restored to its neutral position and the pitch governing motor is de-energized.

An electric temperature circuit may be provided to control the throttle in response to absolute temperature within the combustion chamber in order to maintain that temperature at a preselected value regardless of the speed of the turbine. Such a circuit is described in detail in the aforesaid co-pending application, Serial No. 711,961, filed Nov. 23, 1946. Instead of connecting the temperature responsive regulator to control the propeller pitch governing motor as in the first modification, the temperature circuit energizes and regulates the action of a servomotor which positions the throttle. The throttle is similar to that shown in the previous modification except that a through passageway 43a is provided so that there will be no fluid block at either end of the throttle to prevent its being positioned by the motor. There is a constant pressure drop system operating in conjunction with the throttle inlet and outlet which functions like that previously described. With the arrangement shown, it can be seen that if the temperature in the combustion chamber increases from the preselected value, the temperature correction system will cause the throttle motor to decrease the fuel flow into the combustion chamber until temperature therein drops back to the selected value.

There is a cut-off pilot which is connected to the temperature control lever so that when this temperature lever is set for temperature below a certain value, line 52a is opened to inlet pressure and the constant pressure difference valve by-passes the fuel pump output causing the cut-off valve in line 13 to spring shut and prevent further flow of fuel into the combustion chamber. We contemplate that the cut-off pilot could be connected to the condition lever instead of to the temperature control lever in order to cause the fuel supply to shut off at a certain minimum speed.

Having thus described the present invention so that others skilled in the art may be able to

understand and practice the same, we state that what we desire to secure by Letters Patent is defined in what is claimed.

What is claimed is:

1. A fuel control system for an internal combustion engine comprising a pair of hydraulic pumps arranged to be driven by the engine, one of said pumps being associated with a relief valve adjusted so that the pump forms a source of constant pressure, the other pump being arranged to provide a source of pressure dependent upon engine speed, a cylinder, a fuel supply system for said engine leading into and out of said cylinder, a floating piston in said cylinder for controlling the fuel supply to the engine, and conduits connecting one pump to one end of said cylinder and the other pump to the other end of said cylinder.

2. In combination with an internal combustion engine, a source of fuel supply, a throttle in the line between said source and the engine, means responsive to the inlet and outlet pressures of said throttle to maintain a constant pressure drop across said throttle, control means for the throttle arranged to hold engine speed constant, said control means comprising a servo-circuit sealed from said fuel supply, said servo-circuit including constant pressure line, means whereby said constant pressure tends to open said throttle, a line the pressure of which varies with engine speed, and means whereby said variable pressure tends to close said throttle, pressures in said lines being equal when the engine is at a predetermined speed.

3. A fuel control system for an internal combustion engine having a source of fuel supply and a fuel line, comprising a throttle means for connection in the fuel line, opposed throttle opening and closing lines for moving said throttle, a two-way control valve connected to said actuating lines, a source of fluid under constant pressure urging said control valve in one direction, a source of fluid that varies with engine speed urging said control valve in the other direction, and passageway means in said control valve arranged to connect the constant pressure line to the throttle opening line when the constant pressure exceeds the variable pressure and to connect the variable pressure line to the throttle closing line when the variable pressure exceeds the constant pressure.

4. A fuel control system for an internal combustion engine having a source of fuel supply and a fuel line, comprising a throttle means for connection in the fuel line, opposed throttle opening and closing lines for moving said throttle, a two-way control valve connected to said actuating lines, a source of fluid under constant pressure urging said control valve in one direction, a source of fluid that varies with engine speed urging said control valve in the other direction, passageway means in said control valve arranged to connect the constant pressure line to the throttle opening line when the constant pressure exceeds the variable pressure and to connect the variable pressure line to the throttle closing line when the variable pressure exceeds the constant pressure, and means for manually adjusting one of the pressures leading to said control valve to provide a manual speed adjustment.

5. A fuel control system for an internal combustion engine having a source of fuel supply and a fuel line, comprising a throttle means for connection in the fuel line, opposed throttle opening and closing lines for moving said throttle, a two-

way control valve connected to said actuating lines, a source of fluid under constant pressure urging said control valve in one direction, a source of fluid that varies with engine speed urging said control valve in the other direction, passageway means in said control valve arranged to connect the constant pressure line to the throttle opening line when the constant pressure exceeds the variable pressure and to connect the variable pressure line to the throttle closing line when the variable pressure exceeds the constant pressure, and variable restriction means in one of said opposed throttle lines, the effective restriction being greatest when flow in said lines is

15 in a direction to open the throttle.

6. In a fuel control system for an internal combustion engine, a fuel supply line for the engine, a throttle in the line, opposed hydraulic throttle actuating lines for said throttle, and a restriction device in one of said throttle actuating lines, said restriction device including means movable to decrease the effective restriction in response to fluid flow about the device in a direction tending to close the throttle.

7. In combination with an internal combustion engine, a source of fuel under pressure for the engine, a throttle in the line between said source and the engine, means to maintain a constant pressure drop across the throttle comprising a by-pass line for the throttle inlet line, a by-pass valve spring-urged to close off said by-pass line, said valve having a face subject to throttle inlet pressure tending to open the by-pass, orifice means to permit throttle inlet pressure to slowly

35 build up behind said by-pass valve, a bleed line to bleed off pressure behind said by-pass valve, control means responsive to throttle outlet pressure to open said bleed line as throttle outlet pressure drops causing motion of said by-pass valve toward its open position, said control means closing said bleed line as throttle outlet pressure rises permitting pressure to increase behind said by-pass valve and urge it toward its closed position.

8. In combination with an internal combustion engine, a source of fuel under pressure for the engine, a throttle in the line between said source and the engine, means to maintain a constant pressure drop across the throttle comprising a by-pass line for the throttle inlet line, a by-pass valve spring-urged to close off said by-pass line, said valve having a face subject to throttle inlet pressure tending to open the by-pass, orifice

50 means to permit throttle inlet pressure to slowly build up behind said by-pass valve, a bleed line to bleed off pressure behind said by-pass valve, control means responsive to throttle outlet pressure to open said bleed line as throttle outlet pressure drops causing motion of said by-pass valve toward its open position, said control means closing said bleed line as throttle outlet pressure rises permitting pressure to increase behind said by-pass valve and urge it towards its closed position, and manually controlled pilot means to 55 bleed off pressure behind said by-pass valve.

9. In combination with an internal combustion engine, a source of fuel supply for the engine, a throttle in the line between said source and the engine, a cut off valve in the throttle outlet line 60 to cut off fuel supply to the engine at a predetermined minimum pressure, by-pass means responsive to pressure in the inlet and outlet lines of the throttle to by-pass one of said lines to the source and maintain a constant pressure drop 65 across said throttle independent of pressure

11

variations in the inlet and outlet fuel lines of the throttle, and manually controlled by-pass pilot means connected to said first by-pass means causing it to reduce the throttle inlet pressure whereby the throttle outlet pressure falls below the predetermined closing pressure of said cut-off valve.

10. In combination with an internal combustion engine having a burner, a source of fuel supply for the engine, a throttle in the line between said source and the engine, a remote control system for the throttle separate from the engine fuel supply and arranged to control the fuel supply to the engine, stop means preventing said throttle to close far enough to extinguish the burner in the engine, a cut off valve in the throttle outlet line to cut off fuel supply to the engine at a predetermined minimum pressure, by-pass means responsive to the inlet and outlet pressures of the throttle to maintain a constant pressure drop across said throttle thereby insuring uniformity of engine condition control independent of pressure variations in the inlet and outlet fuel lines of the throttle, and manually controlled pilot means connected to said constant pressure drop means causing it to reduce throttle inlet pressure whereby said by-pass means reduces the throttle outlet pressure below the critical closing pressure of said cut-off valve.

11. A fuel control system for an internal combustion engine comprising a pair of hydraulic pumps arranged to be driven by the engine, one of said pumps being associated with a relief valve adjusted so that the pump forms a source of constant pressure, the other pump being arranged to provide a source of pressure dependent
